ATTORNEY..

UNITED STATES PATENT OFFICE.

FRANK S. ROGERS, OF COWELL, CALIFORNIA.

ROTARY ENGINE.

Application filed July 14, 1924. Serial No. 725,943.

To all whom it may concern:

Be it known that I, FRANK S. ROGERS, a citizen of the United States, residing at Cowell, in the county of Contra Costa, and 5 State of California, have invented new and useful Improvements in Rotary Engines, of which the following is a specification.

This invention relates to improvements in rotary engines and has particular reference 10 to an internal combustion engine.

The principal object of this invention is to provide an engine which will have a greater number of explosions per revolution, a larger stroke and consequently more 15 power per revolution.

Another object is to reduce the number of working parts.

A still further object is to increase the speed, and reduce the weight per horse 20 power and to further decrease the amount of vibration incident to explosive engines.

Other objects and advantages will be apparent during the course of the following description.

25 In the accompanying drawings forming a part of this specification and in which like numerals are employed to designate like parts throughout the same,

Figure 1 is a vertical cross section taken 30 on the line 1—1 of Figure 4, looking in the direction of the arrow A,

Figure 2 is a view similar to Figure 1 looking in the opposite direction to the arrow A,

35 Figure 3 discloses the construction of the packing rings, and

Figure 4 is a vertical cross section of my engine.

In the accompanying drawings wherein 40 for the purpose of illustration is shown a preferred embodiment of my invention, the numerals 5 and 6 refer to two substantially semi-circular castings adapted to be bolted together as at 7 and 8. The casting 6 is provided with supporting lugs 9 and 11. These castings are each provided with a water space as shown at 12 and 13, respectively, within which the customary cooling 45 medium may be circulated. Each casting is further provided with a cored space as shown at 14, which forms the cylinder within which a plurality of pistons 16 and 17 are adapted to travel.

The pistons 16 are preferably formed 50 integral with the rim 18 of spokes 19 hav-

ing a hub 21 which is keyed as at 22 to a shaft 23. This shaft is supported in suitable bearings formed on the castings 5 and 6.

The pistons 17 are connected to the rim 24 by spokes 26 having a hub 27 and freely 60 rotatable upon the shaft 23. The rims of these spokes are in intimate contact with each other as shown at 28 and to prevent leakage of gas therebetween, I provide packing rings 29. Similar packing rings 65 31 are carried upon the rim 18 for the purpose of preventing the leakage of gas between the rim and its contact with the castings 5 and 6.

Similar rings 32 are provided for preventing leakage of gas between the rim 24 and its contact with the castings 5 and 6. The pistons mounted upon each rim overlap the opposite rim as shown in Figure 4.

Lugs 33 and 34 are formed upon two of 75 the spokes 26, which lugs serve to position a rack bar 36 having slots 37 formed therein, through which screws 38 pass, which screws serve to guide reciprocal movement 80 of the rack bar 36.

A roller 39 is mounted upon the end of the rack bar and adapted to travel in a cam 41, which cam is secured to the castings 5 and 6, as best shown in Figure 4. This cam has a structure best illustrated 85 in Figure 2. At 40 I have shown a gear keyed to the shaft 23 which gear meshes with the rack bar 36.

The customary spark plugs are positioned in the castings 5 and 6 as shown at 90 42 and 43, respectively. An explosive charge is admitted to the engine from a carburetor 44 through a manifold 46, which manifold connects with intake ports 47.

Exhaust ports 48 connect with the exhaust 95 manifold 49 in the customary manner. By referring to Figure 3, it will be noted that I have illustrated the packing ring construction where I have shown oil grooves 51 and a spring 52 for keeping the ring in contact with the wall of the casting 5. It is, of course, understood that a plurality of these springs are provided at suitable intervals.

The manner of operating my device is 100 as follows:—

Assuming that the entire device has been assembled, a rotary motion upon the crank 54 will cause the shaft 23 to revolve carrying with it the hub 21, spokes 29, rim 18 and pistons 16. At the same time the gear 110

40 will endeavor to move the rack bar 36 which movement, however, will be limited by the contact of the roller 39 in the cam 41. The result of this crank will then be that 5 assuming that the piston 16 on the right hand side of the drawing of Figure 1, has just passed the intake port, the piston 17 will, at this time, be over the exhaust port so as to close the same, resulting in a charge 10 being drawn through the intake port. At this time the action between the gear 40 and the rack bar 36 will be such that the pistons 17 will be held in the dotted line position of Figure 1, until the piston 17 15 has passed substantially half-way toward the spark plug or firing position. From this point to the point directly below the spark plug, the action between the gear 40 and the rack bar 36 will cause the following piston 17 to travel at the same speed as the piston 16, being considered.

The action of the cam will now cause the piston 17 to move more rapidly than the piston 16, thus compressing the charge 25 between the pistons 16 and 17. During this compression period the piston 16 will move to its dotted line position at the top of Figure 1 and the piston 17 will have reached its dotted line position at the top of the 30 figure. At this time the explosion takes place and the rack bar is now in such a position with respect to the cam that the tendency of the gear to rotate will be practically locked, thus holding the piston 17 35 against explosive action, thus forcing the piston 16 on its course. The burned gas will, of course, be carried toward the exhaust port 48 and shortly after the piston 16 passes the exhaust port, the cam action will then 40 have caused the piston 17 to have speeded up so as to compress the exhaust gases or in other words force them out of the exhaust port.

In brief, the action is one in which a 45 plurality of pairs of pistons move in a circular course one set of pistons at a substantially uniform speed and the other set of pistons at a varying speed, thereby causing the pairs of pistons to approach each

other and separate twice in each explosive 50 cycle.

It is to be understood that the form of my invention herewith shown and described is to be taken as a preferred example of the same, and that various changes in the shape, 55 size and arrangements of parts may be resorted to without departing from the spirit of the invention or the scope of the subjoined claims.

Having thus described my invention, I 60 claim:—

1. In a rotary engine a circular explosive chamber, a shaft centrally positioned with respect to said explosive chamber, a pair of wheels positioned on said shaft, one of 65 said wheels being keyed to said shaft, said wheels having contacting rims, pistons mounted on the rims of each of said wheels, said pistons overlapping the rim of the opposite wheel, a cam mounted adjacent one 70 of said wheels, a segmental gear keyed to said shaft, a rack slidably held on one of said wheels, said rack having a roller engaging said cam for the purpose of causing the wheel to which said rack is attached 75 to move at a varying speed with respect to the movement of the other of said wheels.

2. In a rotary engine a circular explosive chamber, a shaft centrally positioned with respect to said explosive chamber, a pair of 80 wheels positioned on said shaft, one of said wheels being keyed to said shaft, said wheels having contacting rims, pistons mounted on the rims of each of said wheels, said pistons overlapping the rim of the opposite wheel, a cam mounted adjacent one of said wheels, a segmental gear keyed to said shaft, a rack 85 slidably held on one of said wheels, said rack having a roller engaging said cam for the purpose of causing the wheel to which said rack is attached to move at a varying speed with respect to the movement of the other of said wheels, and ports formed in said explosive chamber for the purpose of admitting 90 an explosive mixture to said chamber. 95

In testimony whereof I affix my signature.

FRANK S. ROGERS.
